DESIGN FOR A CASING FOR VACUUM CLEANERS

Theodore A. Schaad, Detroit, Mich., assignor to
Eureka Vacuum Cleaner Company, Detroit,
Mich., a corporation of Michigan

Application June 28, 1937, Serial No. 70,101

Term of patent 14 years

To all whom it may concern:

Be it known that I, Theodore A. Schaad, a citizen of the United States of America, residing at Detroit, in the county of Wayne and State of Michigan, have invented a certain new, original, and ornamental Design for a Casing for Vacuum Cleaners, of which the following is a specification, reference being had therein to the accompanying drawing forming a part thereof, where-in:—

Figure 1 is a perspective view of a casing for vacuum cleaners showing my new design;

Figure 2 is a front elevation of the casing shown in Figure 1; and

Figure 3 is a plan view of the casing shown in Figure 1.

I claim:

The ornamental design for a casing for vacuum cleaners, substantially as shown.

THEODORE A. SCHAAD.
